JAMES D. IRVIN, OF CORYDON, AND BRYSON I. SEWARD, OF BLOOMINGTON, INDIANA.

Letters Patent No. 73,896, dated January 28, 1868.

ALARM FOR GRIST-MILLS.

The Schedule referred to in these Letters Patent and making part of the same.

TO WHOM IT MAY CONCERN:

Be it known that we, JAMES D. IRVIN, of Corydon, county of Harrison, and BRYSON I. SEWARD, of Bloomington, Munroe county, in the State of Indiana, have made new and useful Improvements in Alarms for Grist-Mills, and other purposes; and we hereby declare the following to be a full and exact description of the same, reference being had to the drawings that accompany and form a part of these specifications.

The object of our invention is to provide a machine that will, when attached to a grist or flour-mill, insure each person's flour from his own wheat, by ringing the bell at any given time, indicating that the grist is out. Figure 1, perspective view.

Figure 2, sectional view, showing one side of the machine, the other being a duplicate of the same.

Figure 3, plan view, showing position of the parts when in and out of gear.

Letter A, platform or bed-plate; letter B, movable standards or frame pivoted to the bed-plate, and supporting a bevelled wheel; letter C, bevelled wheel; letter D, adjustable arm attached to the bevelled wheel C; letter E, trigger by which the wheel C is thrown out of gear, its lower end also forming a stop, r, by which it is kept in gear when desired; letter F, lever by which the machine is put in gear; letter G, bell; letter h, hammer on the shank x, on which are several points, i i, indicating the number of strokes that will be given on the bell; letter K, frame attached to the bed-plate in which the running-gear is situated; letter L, pulley attached to a horizontal shaft. Affixed also to this shaft is a perpetual screw, j, which moves the wheel m; this in its turn operates the wheel n. On the end of the shaft supporting the latter is a small bevelled wheel that operates the wheel C. Letter p, spring by which the bevelled wheels C are thrown back when out of gear.

The manner of operating is this: Adjust the arm D on the wheel C so that it will press on the trigger E at the expiration of the time required for the flour to pass through the bolt. Put it in gear by pulling the lever F. It will now run until the arm D comes in contact with the points on the shank of the hammer; this gives the alarm, the number of blows struck on the bell corresponding with the number of points on the shank. The arm D now presses on the trigger and throws the wheels out of gear. The wheel C is carried back by the coiled spring s to its original position or starting-point. The stop r, coming in contact with the lower part of the frame B, prevents it going past that point.

In different mills the time required to carry the flour from the stones through the bolt differs. The adjustable arm D enables us to regulate the time of its running to suit the various mills, and when once adjusted need not be changed.

The parts referred to above are duplicated, thus forming a double alarm.

What we claim, and desire to secure by Letters Patent, is—

1. The movable standards or frames B, the wheels C, provided with the adjustable arms D and stops r, substantially as and for the purposes specified.
2. The triggers E, provided with the stops r, the springs p, acting upon the wheels C, for the purposes set forth.
3. The combination of the running-gear with the wheels C, provided with the adjustable arms D and shanks x of hammers h, furnished with points i i i, the whole forming a double alarm for mills, substantially as herein described.

In testimony whereof, we have signed our names to this specification in the presence of two subscribing witnesses.

JAMES D. IRVIN,
BRYSON I. SEWARD.
